CLAIM

The ornamental design for a torch connector adapted for internal connection to tubular structures, as shown and described.

DESCRIPTION

FIG. 1 is a perspective view of a torch connector adapted for internal connection to tubular structures showing my new design;

FIG. 2 is an end view thereof;

FIG. 3 is a second end view thereof;

FIG. 4 is a side view thereof, with the other side being in mirror image;

FIG. 5 is a top plan view thereof; and,

FIG. 6 is a bottom plan view thereof.
